UNITED STATES PATENT OFFICE.

CHARLEY THERO, OF CHICAGO, ILLINOIS, ASSIGNOR TO UNION SPECIAL MACHINE COMPANY, OF CHICAGO, ILLINOIS, A CORPORATION OF ILLINOIS.

MACHINE FOR OVERCASTING THE EDGES OF FABRICS.

Application filed August 4, 1924. Serial No. 730,015.

This invention relates to new and useful improvements in a machine for overcasting or covering the edge of a fabric or the like.

An object of the invention is to produce

5 an overcasting or edge covering wherein a looper thread is stretched along the edge of the fabric and is secured against said edge by needle thread loops which are in turn secured to the fabric by said looper thread.

Another object of the invention consists in bending the edge portion to be overcasted or covered at an angle to the plane of the body portion of the fabric, passing a needle along 15 one face of the bent portion and through the fabric at the bend therein, carrying the bight of the needle thread loop to the edge of the fabric and securing the needle thread loops by a looper thread extending along the edge 20 of the fabric.

Still another object of the invention is to provide a machine of the above type having a bending bar with a knife edge lying along the needle punctures over which the fabric 25 can be bent and be position so that the needle will pass therethrough at the bend in the fabric.

A further object of the invention is to provide a presser bar for bending the fabric and holding the same against the bar having a 30 knife edge.

A still further object of the invention is to provide a finger and cooperating devices for stretching and positioning the looper 35 thread at the fabric edge.

These and other objects will in part be obvious and will in part be hereinafter more fully described.

In the drawings, which show by way of 40 illustration one embodiment of the invention:—

Figure 1 is a view, partly in section and partly in side elevation, showing a portion of the machine embodying the improvements;

Fig. 2 is a view, partly in section and partly in plan, of the parts shown in Fig. 1;

Fig. 3 is a detail on an enlarged scale of the guide bar and the parts supporting the 50 same;

Fig. 4 is a detail on an enlarged scale of the supporting guide over which the fabric is bent and the means for supporting the same;

Fig. 5 is a detail in plan and on an enlarged scale showing the means for supporting the guide bar and the tension controlling member;

Fig. 6 is an enlarged detail showing the knife edge of the supporting bar;

Fig. 7 is a view, partly in section and on an enlarged scale, from the front of the machine showing the turning over bar with the finger or tongue carried thereby which positions the looper thread;

Fig. 8 is a similar view of the supporting finger and the turning bar taken from the feeding out side of the feed cups or wheels;

Fig. 9 is a plan view of the parts shown in Fig. 7;

Fig. 10 is a sectional view through the needle bar and the needle thread tensioning devices carried thereby, also showing in detail the operating cam for the tensioning devices;

Fig. 11 is a side view of the parts shown in Fig. 10;

Fig. 12 is a top plan view on an enlarged scale showing the edge portion of a fabric covered by the improved process and machine for carrying out the process;

Fig. 13 is a view similar to Fig. 12 but showing the parts in their normal scale;

Fig. 14 is a bottom view of the overcasting or edge covering shown in Fig. 13; and

Fig. 15 is a perspective view on an enlarged scale showing the bend in the fabric and the needle and looper for forming the overcasting.

The invention is directed broadly to a machine for producing an overcasting or edge covering for a hat sweat, and consists in forming needle thread loops which are passed through the hat sweat back from the edge thereof, and wherein the bight of said needle thread loops and the needle thread connecting adjacent loops are laid at the edge of the hat sweat where they are secured by a looper thread which is stretched along the edge and is interwoven with the needle thread so as to be held straight and stretched against the edge of the fabric. This provides a means whereby the hat sweat can be readily secured in another seaming operation to the hat. The invention is, of course, capable of other uses, but this is the particular purpose for which it is designed and, therefore, the process and machine will be

described as related to the forming of an overcasting or edge covering for a hat sweat.

- The process consists broadly in bending the hat sweat at the edge portion which is to be covered or overcasted at an angle to the body portion of the hat sweat and presenting the same to a reciprocating thread carrying needle so that said needle may pass along the lower face of the bent over portion and penetrate the hat sweat at the bend therein. The needle thread loop is caught by a looper and laid against the upper face of the bent over portion with the bight thereof at the edge of the hat sweat. The looper thread carried by the looper passes over the needle thread loop at the bight therein and underneath the shank portion of the needle thread loop on the other side of the bent over portion, and thus the two parts, that is the bight of the needle thread loop and the shank thereof, are secured together and at the same time these parts of the needle thread loop securely hold the looper thread. The looper thread is stretched along the edge of the fabric and is held against the edge of the fabric by the interconnected parts of the needle thread loops and the needle thread extending between adjacent needle thread loops.
- The process is preferably carried out on a machine having rotating feed wheels or cups for supporting the hat sweat, said hat sweat being positioned between said feed cups so as to extend above the same to the extent that the edge portion is to be overcasted or covered. The part which projects above the feed cups is bent over a guide bar having a knife edge, which knife edge engages the hat sweat along the line of the needle punctures. The bent over portion is held against said guide bar by a presser bar. Mounted on the presser bar is a stitch finger which aids in holding the bent over portion of the hat sweat against the guide bar beneath the same and also in positioning the looper thread at the edge of the hat sweat.
- Referring more in detail to the drawings, the sewing machine consists of a suitable frame 1, in which is mounted a reciprocating needle bar 2 carrying a needle 3. The hat sweat or fabric which is to have its edge portion covered or overcasted is supported by the feed cups 4 and 5 which are rotated in the usual way. Cooperating with the needle 3 is a looper 6 carried by a looper support 7. This looper is of the usual construction and has an oscillation at one side of the line of needle punctures which causes its looper to enter a needle thread loop, and then a movement to the other side of the over-casting or edge covering wherein it is positioned so that the needle passes over the looper thread.
- Extending outwardly from the frame 1 is a bracket arm 8 on which is mounted a supporting bar 9 which extends around the inner feed cup 4 at the inside thereof to a position past where the needle crosses said feed cup. The edge of this supporting bar 9 is inclined to form a knife edge 10 over which the hat sweat is bent. Said hat sweat is bent over this knife edge support by means of a presser bar 11. Extending forwardly from the bracket 12 which supports the outer feed cup is an arm 13 on which this presser bar 11 is mounted. A screw 14 passes through the shank of the presser bar and is threaded into the arm 13 directly beneath the same. An adjustable screw 15 is also threaded through the shank of the presser bar 11 and rests on the upper face of the supporting arm 13. Thus it is that the presser bar may be raised and lowered relative to the needle. The screw 14 is loosened and the screw 15 turned down in order to raise the presser bar; the screw 15 is turned up and the screw 14 turned in in order to lower the presser bar. The above means for adjusting the presser bar enables the machine to be set for operating upon different thicknesses of fabric and also provides for more or less of a resilient support for the presser bar.
- The presser bar is also provided with a stitch finger 16 which projects over the needle path. The needle in its reciprocation passes into the guide slot 17. This finger is for the purpose of guiding the looper thread and stretching the same along the edge of the hat sweat. A guide bar 18 is carried by the bracket arm 8 and extends to a point beyond the line of reciprocation of the needle. It is formed with a groove 19 through which the needle passes, and with a guiding lip 20 underneath which the looper thread is laid. This guide bar with its guiding lip 20 operates to position the looper thread at the edge of the fabric and retains it in this position until it is secured there by means of the needle thread loops. This guide bar 18 is secured to the bracket 8 by means of screws 21 and 22. Located between these screws is an axis or fulcrum part 23. It will readily be seen that by manipulating the screws 21 and 22 this guide bar may be rocked on its axis 23 and the outer end thereof raised and lowered.
- The improved process and the operation of the machine for carrying it out may possibly be best understood by reference to Figs. 12 and 15, wherein the hat sweat or fabric having the edge portion to be overcasted or covered is indicated at 24. The edge portion to be covered is indicated at 25. As clearly shown in Fig. 15, this edge portion is bent at an angle substantially at right angles to the plane of the body portion and the bend in the fabric is at a point just above the grip of the feed cups. The needle 3 reciprocates in a line which is sub-

stantially parallel with this bent-over portion and passing underneath the same, so that the needle penetrates the fabric at the bend. Successive needle punctures are indicated at 26 in Fig. 15 of the drawings.

It will be understood, of course, that the knife edge supporting bar is underneath this bent-over portion, and the knife edge lies along the line of the needle punctures. The 10 presser bar lies on top of the bent-over portion and holds it against the supporting bar. The needle passing through the groove 19, see Fig. 3, passes across the end of the knife edge support, and thus can enter 15 the fabric at the bend made in the fabric by the cooperation of the presser bar and the knife edge support. The stitch finger 16 cooperating with the guide bar 18 will retain the edge portion bent over and will 20 also direct the looper thread along the edge 25. The needle thread is indicated at 28. Said needle thread is formed into needle thread loops in the usual way. One of these 25 needle thread loops is indicated at 29 where it has been caught by the looper 6 and carried to the edge of the fabric.

The needle on its next reciprocation will pass between the looper thread, indicated at 30, and the body portion of the looper 6 and 35 will be held by the needle cooperating with the stitch finger and the supporting member 20 along the edge of the fabric. When the looper moves forward to enter the next succeeding needle loop, said looper thread being 40 a heavy thread will draw the shank of the needle thread loop to a position at the edge of the fabric so that the looper thread in effect passes underneath the shank of the needle thread loop and over the bight of the 45 needle thread loop. This is clearly shown in Fig. 12 of the drawings. In other words, the needle thread loop is brought to the edge of the fabric, the shank also lies at the edge of the fabric, and the connecting needle 50 thread between the adjacent loops lies at the edge of the fabric, and the looper thread is interwoven with these parts of the needle thread loops in such a way as to lie straight along the edge. The looper thread may, 55 therefore, serve as an anchoring means for the stitching of the hat sweat to the hat band. By the bending of the edge portion to be covered or overcasted as above described, the parts in the needle thread loops 60 may be brought to the edge of the fabric simply by the looper and the needle, and thus properly positioned for the locking of the same by the looper thread laid at the edge of the hat sweat.

In order that the looper thread may be 65 laid in stretched condition along the edge of the hat sweat or fabric being overcasted or covered, the tension on the needle thread must be very light and for only a portion of the stitch forming cycle. In order to ac-

complish this, on the needle head 31 is a thread tension 32 which reciprocates with said needle head. This tension device is so controlled as to put a tension on the needle thread only for a short time, permitting the 70 needle thread to run without tension for the remainder of the stitch cycle. Said tension consists of a casing 33 in which a pressure bolt 34 moves axially and a tension disk 35 which moves on the housing or casing 33 75 and is connected to the bolt 34 by means of a pin 36. This bolt 34 has a slot 37 at its inner end, in which the pin 36 is placed and subject to the action of the spring 38 between the head 39 of the bolt 34 and the 80 tension disk 35. The housing or casing 33 also has a slot 40 which permits the tension disk 35 to reciprocate subject, of course, to the action of the spring 38. On the needle head is a spring 41 which bears against the 85 end of the pressure bolt 34 and holds the tension for the needle thread open. A cam plate 42 operates on the head 39 of the bolt to move the same to the left, as viewed in Fig. 11, to set the tension. This cam plate 90 42 is so shaped that it only engages this head of the bolt at the time when the needle is at the outer end of its stroke and has passed through the hat sweat. This enables the needle to draw up on the needle thread 95 just for a short time.

The cam plate 42 is carried by an arm 43 which in turn is mounted on a bracket 8 above referred to. Said arm is carried directly by a supporting member 44 which is 100 capable of adjustment in the direction of reciprocation of the needle through the aid of slots 45—45 and the screws 46—46. Said arm 43 can be moved endwise in this supporting member by means of a shifting bolt 105 47. It is understood, of course, that other means may be provided for supporting the operating cam for setting the tension and, therefore, the present structure has only 110 been briefly referred to.

It is obvious that minor changes in details of construction and the arrangement of the parts may be made without departing from the spirit of the invention as set forth in the appended claims.

What I claim as new is:—

1. A machine for forming an edge covering for a fabric, comprising a thread carrying reciprocating needle, means for supporting said fabric with the body portion thereof in a plane at right angles to the line of reciprocation of the needle, means for turning the edge portion of the fabric to be covered at the stitching point so that said edge portion lies in a plane substantially 125 parallel with the line of reciprocation of the needle, means for engaging the needle thread loops and for placing the same against the face of the bent portion of the fabric opposite that passed by the needle as it moves 130

to penetrate the fabric, and means for placing a looper thread along the edge of the fabric and for interlocking the same with the needle thread loops on one face of the fabric and the shanks of the same loops on the other face of the fabric.

2. A machine for forming an edge covering for a fabric including a horizontally reciprocating needle, means for supporting the fabric in substantially a vertical plane, means for bending the portion of the fabric to be covered into a plane at substantially right angles to the plane of the body fabric, and presenting the same to the needle so that said needle passes underneath the bent portion and penetrates the fabric at the bend therein, and means for placing the needle thread loops against the upper face of the portion to be covered and with the bights thereof at the edge of the fabric, means for laying the looper thread in a straight line along the edge of the fabric, said looper thread passing over the loops of the needle thread and underneath the shanks of said needle thread loops whereby said needle thread loops are secured and the looper thread is also securely held along the edge of the fabric, said means for bending the fabric including a supporting bar having a knife edge located substantially at the line of the needle punctures and over which the fabric is bent, and a bending bar for engaging the other face of the fabric and laying the same against said supporting bar, and means for adjustably supporting said bending bar whereby the passage between the bending bar and the supporting bar can be regulated to suit the thickness of the fabric having the edge covering applied thereto.

3. A machine for forming an edge covering for a fabric including a horizontally reciprocating needle, means for supporting the fabric in substantially a vertical plane, means for bending the portion of the fabric to be covered into a plane at substantially right angles to the plane of the body fabric, and presenting the same to the needle so that said needle passes underneath the bent portion and penetrates the fabric at the bend therein, and means for placing the needle thread loops against the upper face of the portion to be covered and the bights thereof at the edge of the fabric, means for laying the looper thread in a straight line along the edge of the fabric, said looper thread passing over the loops of the needle thread and underneath the shanks of said needle thread loops whereby said needle thread loops are secured and the looper thread is also securely held against the edge of the fabric, said means for bending the fabric including a supporting bar having a knife edge located substantially at the line of the needle punctures and over which the fabric is bent, and a bending bar for engaging the other face of the fabric and laying the same against said supporting bar.

4. A machine for forming an edge covering for a fabric including a horizontally reciprocating needle, means for supporting the fabric in substantially a vertical plane, means for bending the portion of the fabric to be covered into a plane at substantially right angles to the plane of the body fabric, and presenting the same to the needle so that said needle passes underneath the bent

portion and penetrates the fabric at the bend therein, means for placing the needle thread loops against the upper face of the portion to be covered and the bights thereof at the edge of the fabric, means for laying the looper thread in a straight line against the edge of the fabric, said looper thread passing over the loops of the needle thread and underneath the shanks of said needle thread loops whereby said needle thread loops are secured and the looper thread is also securely held along the edge of the fabric, said means for bending the fabric including a supporting bar having a knife edge located substantially at the line of the needle punctures and over which the fabric is bent, and a bending bar for engaging the other face of the fabric and laying the same against said supporting bar, and means for adjustably supporting said bending bar whereby the passage between the bending bar and the supporting bar can be regulated to suit the thickness of the fabric having the edge covering applied thereto.

5. A machine for forming an edge covering for a fabric including a horizontally reciprocating needle, means for supporting the fabric in substantially a vertical plane, means for bending the portion of the fabric to be covered into a plane at substantially right angles to the plane of the body fabric, and presenting the same to the needle so that said needle passes underneath the bent portion and penetrates the fabric at the bend therein, and means for placing the needle thread loops against the upper face of the portion to be covered and the bights thereof at the edge of the fabric, means for laying the looper thread in a straight line along the edge of the fabric, said looper thread passing over the loops of the needle thread and underneath the shanks of said needle thread loops whereby said needle thread loops are secured and the looper thread is also securely held against the edge of the fabric, said means for bending the fabric including a supporting bar having a knife edge located substantially at the line of the needle punctures and over which the fabric is bent, and a bending bar for engaging the other face of the fabric and laying the same against said supporting bar, said bending bar having a supporting tongue which holds down the turned over fabric after it passes the needle and which also guides the looper thread onto the edge of the fabric.

6. A machine for forming an edge covering for a fabric including a horizontally reciprocating needle, means for supporting the fabric in substantially a vertical plane, means for bending the portion of the fabric to be covered into a plane at substantially right angles to the plane of the body fabric and presenting the same to the needle so that said needle passes underneath the bent

- portion and penetrates the fabric at the bend therein, means for placing the needle thread loops against the upper face of the portion to be covered and the bights thereof at the 5 edge of the fabric, means for laying the looper thread in a straight line along the edge of the fabric, said looper thread passing over the loops of the needle thread and underneath the shanks of said needle thread 10 loops whereby said needle thread loops are secured and the looper thread is also securely held against the edge of the fabric, said means for bending the fabric including a supporting bar having a knife edge located 15 substantially at the line of the needle punctures and over which the fabric is bent, and a bending bar for engaging the other face of the fabric and laying the same against said supporting bar, said bending bar having 20 a supporting tongue which holds down the turned over fabric after it passes the needle and which also guides the looper thread onto the edge of the fabric, and a guide bar below the turned over portion of the fabric 25 for guiding the looper thread onto the edge of the fabric.
7. A machine for forming an edge covering for a fabric including a horizontally reciprocating needle, means for supporting 30 the fabric in substantially a vertical plane, means for bending the portion of the fabric to be covered into a plane at substantially right angles to the plane of the body fabric and presenting the same to the needle so 35 that said needle passes underneath the bent portion and penetrates the fabric at the bend therein, means for placing the needle thread loops against the upper face of the portion to be covered and the bights thereof 40 at the edge of the fabric, means for laying the looper thread in a straight line along the edge of the fabric, said looper thread passing over the loops of the needle thread and underneath the shanks of said needle 45 thread loops whereby said needle thread loops are secured and the looper thread is also securely held along the edge of the fabric, said means for bending the fabric including a supporting bar having a knife 50 edge located substantially at the line of the needle punctures and over which the fabric is bent, and a bending bar for engaging the other face of the fabric and laying the same against said supporting bar, said bending 55 bar having a supporting tongue which holds down the turned over fabric after it passes the needle and which also guides the looper thread onto the edge of the fabric, a guide bar below the turned over portion of the fabric for guiding the looper thread onto the edge of the fabric, a support for the guide bar having a rib, and screws on opposite sides of said rib for securing the guide bar to the support so that by adjusting the screws the guide bar may be shifted on said rib and adjusted in height relative to 60 the tongue.
8. A machine for forming an edge covering for a fabric including a horizontally reciprocating needle, means for supporting the fabric in substantially a vertical plane, means for bending the portion of the fabric to be covered into a plane at substantially right angles to the plane of the body fabric and presenting the same to the needle so that 65 said needle passes underneath the bent portion and penetrates the fabric at the bend therein, means for placing the needle thread loops against the upper face of the portion to be covered and the bights thereof at the edge of the fabric, means for laying the looper thread in a straight line along the 70 edge of the fabric, said looper thread passing over the loops of the needle thread and underneath the shanks of said needle thread loops whereby said needle thread loops are 75 secured and the looper thread is also securely held against the edge of the fabric, said means for bending the fabric including a supporting bar having a knife edge located substantially at the line of the needle punctures and over which the fabric is bent, and a bending bar for engaging the other face of the fabric and laying the same against 80 said supporting bar, said bending bar having a supporting tongue which holds down the turned over fabric after it passes the needle and which also guides the looper thread onto the edge of the fabric, a guide bar below the turned over portion of the fabric for guiding the looper thread onto the edge of the fabric, a support for the guide bar having a rib, and screws on opposite sides of said rib for securing the guide bar to the support so that by adjusting the screws the guide bar may be shifted on 85 said rib and adjusted in height relative to the tongue.
9. A machine for forming an edge covering for fabrics comprising a thread carrying reciprocating needle, means for supporting the fabric with the body portion thereof in a plane at an angle to the line of reciprocation of the needle, whereby said needle will penetrate said fabric, means for turning the edge portion of the fabric to be covered at the stitching point, so that said edge portion lies in a plane substantially parallel with the line of reciprocation of the needle, and means co-operating with said needle for laying a looper thread at the edge of the fabric interlocked with said needle thread loops.
10. A machine for forming an edge covering for fabrics comprising a thread carrying reciprocating needle, means for supporting the fabric with the body portion thereof in a plane at an angle to the line of reciprocation of the needle, whereby said needle will penetrate said fabric, means for turning the edge portion of the fabric to be covered at the stitching point, so that said edge portion lies in a plane substantially parallel with

the line of reciprocation of the needle, means interlocking the same with the needle thread
for engaging the needle thread loops and loops on one face of the fabric and the
for placing the same against the face of the shanks of the same loops on the other face ¹⁰
bent portion of the fabric opposite that of the fabric.

5 passed by the needle as it passes to penetrate In testimony whereof, I affix my signature.
the fabric, and means for placing a looper
thread along the edge of the fabric and for

CHARLEY THERO.
